UNITED STATES PATENT OFFICE.

DAVID R. BONE, OF OGLESBY, TEXAS.

KILN.

1,303,760.

Specification of Letters Patent. Patented May 13, 1919.

Application filed September 9, 1918. Serial No. 253,204.

To all whom it may concern:

Be it known that I, DAVID R. BONE, a citizen of the United States of America, residing at Oglesby, in the county of Coryell and State of Texas, have invented certain new and useful Improvements in Kilns, of which the following is a specification.

My invention relates to improved construction for kilns and the object is to provide a method of producing heat for kilns, furnaces for burning lime and clay products and similar products, to provide apparatus for feeding fuel in powdered form by gravity to the combustion chambers and at the same time preventing cold or normal air from entering the chambers with the fuel, to provide a construction by which all cold or normal air is prevented from entering the combustion chambers, to provide apparatus for preheating the air for combustion purposes, furnishing enough oxygen to oxidize and combine with all carbon elements, and for transmitting the heat so produced to places where it is to be used. Another object is to provide apparatus by which lignite and other cheap fuel can be used economically and with a saving of labor and expense. This invention is in part practically a continuation of my copending application, Ser. No. 182,421, filed July 24, 1917, and the object of the present application is to protect various combined improvements for carrying out the heat producing process set forth in the patent granted to me on October 15, 1918, No. 1,281,902.

Other objects and advantages will be fully explained in the following description and the invention will be more particularly pointed out in the claims.

Reference is had to the accompanying drawings which form a part of this application.

Figure 1 is a plan view of the improved kiln, partly broken to show the improved construction. Fig. 2 is a side elevation of a portion of a kiln. Fig. 3 is a broken longitudinal vertical section, of the kiln, showing two compartments with wares to be burned and one compartment empty. Fig. 4 is a vertical cross-section of the stoking device, or stoker. Fig. 5 is a vertical section of the rotary discharge feeder. Fig. 6 is a vertical cross-section of the kiln. Fig. 7 is a diagrammatic plan view of the furnace. Fig. 8 is a diagrammatic vertical section of

all the compartments for illustrating and explaining the method of operation.

Similar characters of reference are used to indicate the same parts throughout the several views.

The improvements are embodied in what is known as a continuous kiln or ring kiln. The kiln is provided with two walls 1 and 2, which are connected at their ends by curved perpendicular walls 3 and 4, being continuations of the side walls 1 and 2. A central wall 5 divides the kiln centrally but does not extend to the ends thus providing an endless or continuous space for forming compartments within the walls in contiguous series. The compartments are formed by placing permanent stationary walls or partitions 7 of masonry connected to the central wall 5 and the outer walls 1, 2, 3, and 4. The compartments are indicated by 6^a, 6^b, 6^c, 6^d, 6^e, 6^f, 6^g, 6^h, 6ⁱ, 6^k, 6^l, 6^m, 6ⁿ, 6^o, 6^p, 6^q, 6^r, 6^s, and 6^t. It is apparent that the number of compartments may be increased or decreased and various changes in the sizes, proportions and construction of the several parts may be made without departing from my invention. The kiln is provided with a cover or platen 8. Openings 23 in the platen continue down through the wares in the furnace, the openings through the wares constituting downwardly projecting shafts for the passage of burning fuel and heat. These openings are closed by caps 10 which are opened only when fuel is to be fed to the combustion chamber or compartment. Fuel is fed through stoking devices shown in detail in Figs. 4 and 5. The fuel feeder includes a hopper or hoppers 11 and a rotary discharge feeder 12. The feeder has a plurality of recesses 13, corresponding generally to the number of openings 23 in a compartment of the kiln to be supplied with fuel. The discharge feeder 12 is mounted in a casing 14 which communicates with the hopper 11 and a discharge outlet 15, through which fuel is fed to the recesses 13 in the rotary feeder 12. The construction of the stoking devices is such that the connection of the discharge outlet 15 can be connected with an opening 23 substantially excluding air from the atmosphere so that the fuel can be fed to the combustion chamber without admitting air, or so that the admission of air will be so small that it will not interfere with the fuel burning process in the kiln sufficiently to dis-

sipate heat. The stoking devices may be moved about over the kiln in the usual manner (not necessary to be described). The goods are to be placed in and arranged in 5 the furnace or burning chamber in the usual manner. Passages or heat transferring ducts 16 are formed under the masonry partitions 7 for the passage of heat from one compartment to the other in series. These passages or ducts are closed and opened by 10 dampers or valves 17 set edgewise and provided with handles 28. Two dampers 17 with two handles 28 are necessary because the heat may progress from either direction. 15 A damper or valve is kept closed until it is necessary to transfer the heat to the next compartment or burning chamber. The different compartments or burning chambers are provided with doors 18 for convenience 20 in placing the wares in the furnace. Other openings 22 are provided next to the ground for outside firing, and these openings may be closed and kept closed when necessary. The upright provisional firing shafts 23 are 25 provided at suitable intervals in the brick or other goods, and these may extend down to the provisional channels 25 which are provided in the goods along the floor of the furnace so that there will be communication of 30 the shafts 23 with the channels 25. Openings 24 are provided in the floor of the furnace leading from the channels 25 to underground flues 21. There may be any suitable 35 number of openings 24 for each burning chamber 6, all opening into a single flue 21. The flues 21 all lead to a smoke tunnel 19 and each flue 21 is provided with a damper 26 located at the discharge into the tunnel 19. Manholes 27 are provided for entrance into 40 the tunnel 19 so that a person can go down into the tunnel to seal the dampers 26 airtight. This may be done with plastic material to keep air excluded while the process of curing the wares is going on. 45 The flues above described constitute a part of the system of underground flues which are used in the operation of the herein described kiln. This system is preferable and gives more satisfactory service than kilns which 50 have the flues at one side or the other in the walls of the kilns. The flues 21 cause a spreading or uniform distribution of the heat by reason of the connection with the openings 24 and draft channels 25, which 55 communicate with the shafts 23. The large smoke tunnel 19 is placed below the surface and encircles the entire kiln and communicates with the suction fan 20. The smaller draft flues 21 lead from the center of the 60 kiln outwardly into the main flue or tunnel 19. When the fan is in operation it will draw all smoke out of the kiln and there is an advantage in having the tunnel 19 entirely around the kiln because the fan will draw in either direction. In this manner, certain 65 gases, waste and smoke will pass to the large smoke tunnel and out through the fan 20. By means of the dampers 26 and the passages 16 under the partition walls and dampers 17, the heat can be made to progress 70 in the kiln so that the heat which has already served to heat the wares in one burning chamber will be transmitted to the next burning chamber or compartment forward. The work progresses in the ordinary way; 75 that is, when the wares are burned in one compartment, the next compartment forward will then be treated in the same manner. 80 The passages 16 under the partition walls 7 make it possible for the heat produced in one burning chamber to pass down under the partition walls and thus become transferred into the next compartment when and after the heat has finished its work of 85 burning the wares in one compartment. The heat that is thus transferred into the next compartment is controlled by dampers 17 which covers the openings 16 under the partitions 7. This same heat is reinforced with 90 additional heat produced by feeding fresh fuel through the firing holes 23. When the burning of wares in this compartment is finished, the same process is continued in 95 the next compartment and so on, thus keeping up a continuous burning system by feeding fresh fuel by gravity in powdered form through firing holes provided in the top or platen 8. This top covering is made in the form of a platen over the top of the kiln 100 and made from slabs of fireproof material and bricks with a covering of sand on top. The powdered fuel is fed by gravity into the kiln without allowing any of the atmosphere or cold air to enter into the burning of the 105 fuel, and this is accomplished by means of the stoking devices above described and shown in the drawings. The burning of products is done within a compartment of the kiln which is so perfectly closed that 110 no draft or air is allowed to enter, except a certain amount which is only permitted to come through the compartments in which the burning of the products has just been finished, and wherein there is still remaining a high degree of heat and which is transmitted through ducts 16. The air thus becomes preheated before it reaches the chamber in which it is to serve for oxidizing the fuel gases and in bringing about a complete 115 combustion of all fuel. In this construction no air is permitted to come in contact with the combustion gases, except what has been preheated, and the principal object in building the solid partition walls in this kiln is 120 especially for the purpose of excluding air as stated, and the producing and conserving of heat is better controlled by doing away with the ordinary removable partitions in use in continuous kilns, which are usually 125 130

made of paper and other temporary arrangements that cannot be made to exclude all air from the combustion compartment of the kiln. Forward and ahead of the burning zone, an outlet controlled by an air-tight damper is provided for the passing out of certain gases, waste heat and smoke into the large smoke tunnel 19, to the fan or to a chimney. This escape or evacuation process provides a draft, causing the main heat to progress, advancing forward as the burning of the product is being finished. Through this large smoke tunnel, hot air, certain gases and waste heat are drawn from the kiln and are driven through a system of tunnels or pipes. Other openings 22 into each compartment are provided in the outside walls next to the ground to make a slow smoky fire to carry out the moisture from the green wares through the top of the kiln in the same way as the water smoking process has always been done in the old time open top kilns. These openings are closed up air-tight as soon as the water smoking is complete.

The operation may be followed in the order designated by the compartments, as diagrammatically arranged in Fig. 8. 6^a indicates the chamber which is being filled with green wares and 6^b designates the chamber which has just been emptied. 6^c represents the chamber from which the finished goods are removed. 6^a, 6^e, 6^f, 6^g and 6^h indicate the chambers having various temperatures, and in which the finished product is being slowly cooled off, and through which the preheated air is supplied to the chambers 6ⁱ and 6^j, as the direction of arrow heads on the drawings shows. Fuel is fed into those chambers through holes 23 in the top covering to increase the degree of heat as necessary for the burning of the wares. 6^k, 6^l, 6^m, 6ⁿ, 6° and 6^p, show chambers which have gradually decreasing temperatures, and through which the heat passes from the fires in chambers 6ⁱ and 6^j, as shown by the arrows pointing to the passages or openings. 6^q and 6^r indicate chambers separated by the partition walls with openings 16 closed up air-tight. In these chambers the green wares are being water smoked from the fuel in openings 22, with door opening 18 on the outside wall closed up temporarily. Water smoking has just been started in chamber 6^r, the fires in chambers 6^s, 6^t, and 6^u being each about a day or so older than the next adjacent, so that the temperatures in the chambers vary as indicated in chambers 6^a, 6^b, 6^s, and 6^t.

The advantages of the improved kilns are derived from the following named outstanding features:

First. The construction of the partition walls between the compartments or burning chambers is stationary instead of removable.

Second. Under the stationary partitions, heat conveying ducts make it possible to control the heat and draft with regulation in each of the compartments better than when such partitions are made temporary and have to be removed.

Third. Having under the said stationary partitions the heat and draft conveying ducts, it is possible by opening the same by removing the damper or valve to have the heat and draft enter into the next compartment in a more regulated way than it is possible to be done in cases where the whole partitions have to be removed.

Fourth. By a plurality of draft openings in the floor of the kiln chamber in straight lines across from inside wall to outside wall, the heat and draft are made to spread the full width of the burning chamber which is not the case where the draft openings going out of the chamber or kiln are made either at one side or the other or are made in any of the walls of the kiln.

Fifth. The large draft tunnel being outside the kiln connecting with the smaller flues 21 in each burning chamber, provides possible means for entering the said tunnel through numerous manholes located at points where the smaller flues 21 connect with the large tunnel 19 and makes it easy to enter the tunnel 19 for the purpose of plastering around the flue dampers for making the same air-tight while the kiln is in operation.

Sixth. That the entire construction of this kiln is economical is in evidence because the need of expensive construction, both in the center wall and the outside wall, is eliminated. The plans are simple and the walls may have the same construction as the old original kiln walls used in the common open old type field kilns.

Seventh. The efficiency of this burning process is made possible by being provided with means for excluding all the air from the chamber which is under process of burning the goods and at the same time permitting a sufficient amount of preheated air to come in through goods or wares that have already been cured and which still retain a high degree of heat.

What I claim is,

1. A kiln comprising a central wall and an outer wall surrounding said central wall and spaced therefrom forming a space around said central wall, means for dividing said space into a series of burning chambers, a floor for said chambers having pluralities of openings therein, a smoke tunnel surrounding said outer wall, a series of tunnels or flues connecting the openings in said floor with said surrounding tunnel, and means for creating a draft in said surrounding tunnel.

2. A kiln of the continuous burning type for burning clay products having a plurality of burning chambers connected in series,

permanent masonry walls forming partitions between said chambers and a floor therefor having passages under each partition wall for progressive feeding of preheated air for ward from cooling off chambers, means for closing and opening said passages, means for feeding by gravity fuel in powdered form to said chambers and for preventing cold or

normal air from entering with the fuel, said floor having openings therein, an underground outside continuous smoke tunnel surrounding said kiln and underground flues connecting said openings with said tunnel. 10

In testimony whereof, I set my hand, this 4th day of September, 1918.

DAVID R. BONE.
